UNITED STATES PATENT OFFICE.

EDWARD A. GEOGHEGAN, OF ERIE, PENNSYLVANIA.

APPARATUS FOR SUPERHEATING STEAM.

1,072,598.

Specification of Letters Patent. Patented Sept. 9, 1913.

Application filed April 25, 1911. Serial No. 523,228.

To all whom it may concern:

Be it known that I, EDWARD A. GEOGHEGAN, a citizen of Great Britain, residing at Erie, in the county of Erie and State of Pennsylvania, have invented certain new and useful Improvements in Apparatus for Superheating Steam; and I do hereby declare the following to be a full, clear, and exact description of the invention, such as will enable others skilled in the art to which it appertains to make and use the same, reference being had to the accompanying drawings, and to the letters of reference marked thereon, forming part of this specification.

My invention relates to improvements in processes and methods of super-heating steam by means of which the proper proportions of oxygen and hydrogen contained in steam are at all times preserved.

In the processes of super-heating steam as heretofore practiced the column of steam to be superheated is either exposed to the action of heat in a single tube, or is divided among a number of smaller tubes, and in either of which cases the temperature of the steam is almost instantly raised to substantially double the number of degrees at which it issues from the steam generator. One of the results of these methods of superheating steam is that a large proportion of the oxygen is transformed into solids of a more or less corrosive nature which adhere to the tubes of the superheating apparatus and parts of motors which may come into contact therewith, and the residue is in the nature of hydrogeh gas which will quickly volatilize lubricating agents, and is highly explosive when exposed to a flame or spark.

In my improved process I divide the column of steam to be superheated by passing the same through a group of tubes of less diameter than the tube which supplies the steam to the super-heating apparatus, and then subject said group of tubes to heat of moderate intensity, which acts only upon the particles of steam which come in contact with the inner surfaces of the walls of the tubes. The steam having passed through the first group of tubes is then preferably collected into a single body or column in which all the particles of steam intermingle and mix together during which action all those particles of steam which came into most direct contact with the heated surfaces of the

tubes composing the first group of tubes from which they have absorbed heat give off a portion of the heat thus acquired which is immediately absorbed by the particles of steam of lower temperature, thus equalizing the temperature of all the particles being intermixed. This intermixed single body or column of steam is again subdivided by passing it through a group of a still greater number of tubes, and preferably of less diameter, than the first group. This second group of tubes is also subjected to the action of heat, preferably of greater intensity than in the case of the first group, which heat again acts to raise the temperature of those particles of steam which come in contact with the inner surfaces of the walls of the tubes. After passing through the tubes of the second group of tubes the steam is again collected into a single body wherein the particles thereof again intermingle and mix together as before. This process of alternately subdividing and re-collecting and intermixing is successively repeated until the required degree of temperature has been obtained, each successive group of tubes being composed of a greater number of tubes, and preferably of less diameter than in the group immediately preceding, and each successive group being subjected to heat, preferably of greater intensity than its immediately preceding group.

I have herein described the application of heat of progressively increasing intensity to the several successive groups of tubes, as a preferable method of applying heat in practising my improved process and method of superheating steam, but the same may be successively practiced by the application of heat of equal intensity to each and all of the groups of tubes without departing from the spirit of my invention, and therefore I do not limit myself thereto. By this process I am enabled to gradually raise the temperature of steam to almost any number of degrees of heat without changing the relative proportions of oxygen and hydrogen of which steam is composed.

I have in the accompanying drawings illustrated a convenient apparatus suitable for practising my improved process for superheating steam in which:

Figure 1 is a side view partially in elevation and partially in section of an appara-

110

tus suitable for practising my improved process. Fig. 2 is a transverse section of the same on the line $x-x$ in Fig. 1. Fig. 3 is a top or plan view thereof with parts there-
5 of broken away.

In these drawings, A, A', A², A³, A⁴, A⁵, A⁶, and A⁷, indicate a series of headers, the headers, A⁷ and A², A³ and A⁴, A⁵ and A⁶ communicating with each other by means of 10 the openings, a, a', and a², in the abutting end walls thereof. The headers, A and A', are connected by means of the U-shaped tubes, B. The headers, A² and A³, are connected by means of U-shaped tubes, B, which are more in number and smaller than 15 the tubes, B'. The headers A⁴ and A⁵, are connected by means of U-shaped tubes, B², which are more in number and smaller than the tubes, B'. And the headers, A⁶ and A⁷, are connected by means of U-shaped tubes, B³, which are more in number and smaller 20 than the tubes, B².

C, indicates a steam supply pipe leading from a steam generat^{or} (not shown) to the 25 first header, A, through a suitable shut-off valve, C', and D, indicates a discharge pipe leading from the last header, A⁷, through a suitable shut-off valve, D'.

E, indicates a discharge pipe leading from 30 the header, A³, through a suitable shut-off valve, E', and F, indicates a discharge pipe leading from the header, A⁶, through a suitable shut off valve F'.

In Fig. 1 of the drawings the valves, E' 35 and F', are shown as being closed, but if for any purpose it is desirable to use steam that has only passed through the tubes, B and B', or through the tubes, B, B' and B²; the shut-off valve, E', or F', may be opened 40 for that purpose.

The several headers, A, A' &c., are supported upon transverse supports, G, which in turn are supported by the walls, H, H', of the fire chamber, H', so that the U-shaped tubes, B, B', &c., will extend downward into the fire box, H'.

J, indicates grate-bars, and K, indicates a smoke flue leading from the fire box, H'.

I do not, however, claim to have invented 50 a steam super-heater in which the heating tubes are spaced closer together in the direction of the flow of the gases, to equalize the

absorption of heat throughout the tubes, as that forms no part of my invention.

Therefore having fully described my im- 55 proved process and method of superheating steam and illustrated and described the construction of convenient apparatus for practising the same, what I claim as new and desire to secure by Letters-Patent is: 60

1. In a device of the class described, the combination of a heating chamber, a furnace for supplying hot gases of combustion to said chamber, and a series of steam conveying tubes in said chamber, which tubes 65 increase in number and decrease in diameter in the direction of the flow of steam there- through, substantially as set forth.

2. In a device of the class described, the combination of a heating chamber, a fur- 70 nace for supplying hot gases of combustion to said chamber, and a series of groups of steam conveying tubes in said chamber, the tubes of each successive group increasing in number and decreasing in diameter in the 75 direction of the flow of steam therethrough, substantially as set forth.

3. In a steam superheating apparatus, a series of heating tubes arranged in groups, each group of said tubes containing a great- 80 er number of tubes than the preceding group, a series of headers with which said groups of tubes communicate adapted to conduct steam discharged from one group of tubes into the next succeeding group of 85 tubes, and means for applying heat to said tubes, substantially as set forth.

4. In a steam superheating apparatus, a series of heating tubes arranged in groups, each group of tubes containing a greater 90 number of tubes of lesser diameter than the group immediately preceding, a series of headers with which said groups of tubes communicate adapted to conduct steam discharged from one group of tubes into the 95 next succeeding group of tubes, and means for applying heat to said heating tubes, substantially as set forth.

In testimony whereof I affix my signature, in presence of two witnesses.

EDWARD A. GEOGHEGAN.
